UNITED STATES PATENT OFFICE.

JOE ROOKS, OF ANDERSONVILLE, GEORGIA.

BED BOTTOM.

Application filed May 11, 1928. Serial No. 276,964.

My invention relates to bed bottoms, and is an improvement over that shown in my Patent No. 1,427,020 granted August 22, 1922.

5 It is an object of the invention to provide a stronger and more durable device of this character, suitable for use with an iron bedstead, and one in which the bed bottom along the middle may be adjusted to level 10 up the mattress and prevent the same from sagging, but having a certain amount of resiliency; all as will be hereinafter more particularly set forth and claimed.

Referring to the accompanying drawings 15 which are made a part hereof and on which similar reference characters indicate similar parts,

Figure 1 is a top plan view illustrating one application of my invention;

20 Figure 2 is a vertical section on a line 2—2 of Figure 1;

Figure 3 is a vertical section taken on a line 3—3 of Figure 2.

In the drawings reference character 10 25 indicates the head and 11 the foot of an ordinary iron bedstead, connected by angle iron side bars 12. In the usual construction slats or patent springs are placed on the horizontal flanges 13 of the side bars, such 30 slats frequently sagging and the patent springs being less comfortable than the old type of springs used with the slats. As de- 35 scribed in my patent above mentioned, instead of using slats which extend entirely across the bed, I have severed the slats along 40 the median line of the bed, and instead of using wood I have substituted metal bars, a pair of such transverse bars 14 and 15 taking the place of a single slat. Said transverse 45 bars 14 and 15 are secured at their outer ends to the side bars 12 by means of rivets or bolts 16, and have their inner ends secured by rivets or bolts 17 to a pair of oppositely disposed parallel longitudinal hanger 50 bars 18, such bars being mounted back to back, and with their upper horizontal flanges extending outwardly over the transverse bars 14 and 15. The longitudinal supporting bars 18 are connected by a plurality 55 of hinge members each comprising sections 19 and 20 longitudinally slotted at 21 to permit longitudinal adjustment of the respec-

tive hinge sections, bolts or other fastening means 22 being employed for securing the sections firmly together in fixed adjusted 55

relation. On the under side of each of said longitudinal hanger bars 18 is pivotally supported a depending arm 23 which co-operates with an opposed depending arm 24 on the adjacent bar, said depending arms being 60 cut away at one side so that when the depending bars are swung to overlapping relation they form a slot between them, such depending arms being limited in their overlapping relation by their upper ends which 65

engage the horizontal portions of the longitudinal bars 18. A helical spring is inserted around the members 23 and 24 against which rests a transverse rod 26, which has its extremities secured to the rivets or bolts 16 for 70 supporting the central part of the bed bottom in the desired position, a turn buckle 27 being also provided by means of which the proper adjustment can be had and the middle portion of the bed held at the proper 75 height.

It will be obvious to those skilled in the art that various changes may be made in my device without departing from the spirit of the invention, and I, therefore, do not 80 limit myself to what is shown in the drawings and described in the specification, but only as set forth in the appended claims.

Having thus fully described my said invention, what I claim as new and desire to 85 secure by Letters Patent, is:

1. A bed bottom comprising two juxtaposed sections each comprising a frame having spaced transverse bars extending thereacross, adjustable hinges connecting the said sections, overlapping arms depending from said bottom under one of said hinges the said arms being pivoted to each of said sections and one of said arms having a cut-out portion in its extremity to form a slot between the arms, a spring surrounding said arms, and an adjustable tensioning element secured to opposite sides of said bottom and extending under said spring through said slot for adjusting the height of the middle 95 100 of said bed bottom, substantially as set forth.

2. A bed bottom comprising two juxtaposed sections comprising a frame having transverse bars extending thereacross, ad-

justable hinges connecting said sections, an arm depending from each section and overlapping an arm of the other section, a spring about said arms, and an adjustable tensioning element secured to opposite sides of said bottom and extending beneath said spring between the arms for adjusting the height

of the middle of said bed bottom, substantially as set forth.

In witness whereof, I have hereunto set my hand at Andersonville, Georgia, this 8th day of May, A. D. nineteen hundred and twenty-eight.

JOE ROOKS.
